(57) **CLAIM**

The ornamental design for a front bumper assembly for a motor vehicle, as shown and described.

DESCRIPTION

FIG. 1 is a perspective view of a front bumper assembly for a motor vehicle;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines illustrate portions of the front bumper assembly for a motor vehicle that form no part of the claimed design.

1 Claim, 6 Drawing Sheets
